UNITED STATES PATENT OFFICE.

CHARLES J. VENN, OF CHICAGO, ILLINOIS.

DESIGN FOR A TIRE-TREAD.

54,975.

Specification for Design.

Patented Apr. 20, 1920.

Application filed November 25, 1919. Serial No. 340,686. Term of patent 14 years.

To all whom it may concern:

Be it known that I, CHARLES J. VENN, a citizen of the United States, residing at Chicago, Cook county, Illinois, have invented a new, original, and ornamental Design for a Tire-Tread, of which the following is a specification, reference being had to the accompanying drawing, forming part thereof.

Figure 1 is a face view of the tire tread,

and Fig. 2 is a section on the line 2—2 of Fig. 1.

I claim:

The ornamental design for a tire tread, substantially as shown.

In testimony whereof, I have signed my name to this specification this 8th day of November, 1919.

CHARLES J. VENN.
